CLAIM

The ornamental design for a scalp brush as shown and described.

DESCRIPTION

FIG. 1 is a top perspective view of a scalp brush showing my new design;

FIG. 2 is a front perspective view thereof;

FIG. 3 is a bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a cross-sectional view thereof taken along the line 10-10 of FIG. 9;

FIG. 11 is a cross-sectional view thereof taken along the line 11-11 of FIG. 9; and,

FIG. 12 is an enlarged view of an indicated portion of FIG. 9.

The broken line portions of the scalp brush in FIGS. 1-7 and 9-12 represent unclaimed portions of the claimed design and form no part thereof.
